UNITED STATES PATENT OFFICE.

THEODORE S. VERY, OF BOSTON, MASSACHUSETTS.

METHOD OF VENTILATING SEWERS AND DRAINS.

SPECIFICATION forming part of Letters Patent No. 242,169, dated May 31, 1881.

Application filed May 4, 1880. (No model.)

To all whom it may concern:

Be it known that I, THEODORE S. VERY, of Boston, in the county of Suffolk and State of Massachusetts, have invented certain Improvements in Methods of Ventilating Sewers and Drains, of which the following is a specification.

This invention relates to methods of ventilation for preventing the introduction of sewer-gas into buildings. It is fully set forth in the accompanying drawings, forming part of this specification, in which—

Figure 1 is a plan view of a portion of the basement of a building, showing the drains constructed in the manner embodying my invention. Fig. 2 is a vertical longitudinal section on line *xx*, Fig. 1.

In these figures the same letters refer to the same parts.

It is well known that the passage of sewer-gas from the street-drains back through the house-drains, from whence it escapes through the water-closets and other plumbing works into the house, forms a prolific source of disease. The traps at present used to prevent the introduction of this gas frequently prove inadequate for the purpose, and to secure a perfect barrier to its entrance requires careful workmanship and a resort to costly expedients in carrying out the plumbing arrangements of the building.

My invention is designed to provide a simple and thoroughly efficient means of preventing the backward current of this gas from the street to the house, and at the same time secure a powerful outward draft from the house to the main. To this end I make use of the device which I will now proceed to describe and claim.

In the drawings, *M* represents the street main or sewer, with which the house-drains are connected by the trunk drain *H*. This trunk drain receives the upright soil-pipe *S*, extending from the water-closets and other plumbing works in the upper part of the house, and the branch drain *C* from works in a different part of the building.

B represents a blowing apparatus, of the Sturtevant or any approved pattern, connected by the pipe *P* with the trunk drain *H*. The pipe *P* enters the trunk drain at an acute angle at some point between the last branch connection with said trunk drain and its outlet into the street-main.

The blowing apparatus *B* is operated by any

suitable motor in the usual manner, and is adapted, when in operation, to force a strong current of air through the pipe *P*, and outwardly through the trunk drain *H* into the sewer *M*. By this arrangement it is obvious that a strong outward current is maintained in the trunk drain *H*, and all reverse or backward action of sewer-gas from the main to the house is effectually prevented. The outward current of air also serves to free the branch pipes *C S* from foul air.

I do not limit myself to any particular form of blowing apparatus, as the principle of my invention can be carried out by forcing a jet of steam into the drains, or by any approved means of creating a strong outward draft therein.

It is obvious that my invention is applicable to any sort of building, and that any number of branch drains may enter the trunk drain without interfering with its operation, it only being necessary to connect the blower with the trunk drain at some point outside the last branch connection.

My invention may also be applied, on a larger scale, for ventilating the street-sewers, the blowing apparatus in such a case being placed in immediate connection therewith. When used for ventilating the drains of a building only, the blower may be placed in either story, as may be most convenient, and the air or steam transmitted from it to the drain by hose or any other approved conductor.

Having thus described my invention, what I claim is—

1. The improvement in the art of ventilating sewers herein described, which consists in forcing a current of air outward from a building into the main and branch drains connected with such building, whereby the flow of sewer-gas into the building is prevented, substantially as specified.

2. The combination of blowing or air-forcing apparatus with the drains of a building, substantially in the manner and for the purpose set forth.

In testimony whereof I have signed my name to this specification, in the presence of two subscribing witnesses, this 29th day of April, A. D. 1880.

THEODORE S. VERY.
